UNITED STATES PATENT OFFICE.

WILLIAM G. LAMB AND ORANGE S. LAMB, OF WATERLOO, IOWA.

RESILIENT BRAKE-HANGER.

1,093,864.

Specification of Letters Patent.

Patented Apr. 21, 1914.

Application filed November 16, 1912. Serial No. 731,780.

To all whom it may concern:

Be it known that we, WILLIAM G. LAMB and ORANGE S. LAMB, citizens of the United States of America, and residents of Waterloo, Blackhawk county, Iowa, have invented 5 certain new and useful Improvements in Resilient Brake-Hangers, of which the following is a specification.

Our invention relates to improvements in 10 resilient brake-hangers, and the object of our improvement is to furnish means for supporting a spring-hanger and maintaining it and the brake-head in a desired relation to prevent slackness and keep the parts in a 15 suitable position adjacent to the wheel to be acted on. This object we have accomplished by the means which are hereinafter described and claimed, and which are illustrated in the accompanying drawings, in 20 which:

Figure 1 is a side elevation of our improved resilient brake hanger as supporting a brake-head in juxtaposition to a car-wheel, parts being broken away. Fig. 2 is a rear 25 elevation of the parts shown in Fig. 1, and Fig. 3 is a perspective detail view of the spring-hanger as disassembled from the support and from the brake-head.

Similar numerals of reference denote 30 corresponding parts throughout the several views.

The numeral 21 denotes a brake-shoe located in operative juxtaposition to the tread of the car-wheel 22, and having perforated 35 lugs on its rear face adapted to register with projections on the forward face of the brake-block 15, a removable pin 16 serving to secure said parts together detachably. The rear part of said brake-block is formed 40 with two recesses on upper and lower sides of a projection 29. Brake-bars 18 and 19 are secured in said recesses to said projection 29 by means of a screw, and short ribs 30 on said bars are seated in grooves in said projection to secure them from rocking. A 45 brake rod 17 is secured between the bars 18 and 19 by means of a bolt 27 and a nut 26.

The numeral 1 denotes a brake-hanger 50 formed of a flat plate of spring-steel or other resilient material and having on the same face of each end a flanged-over lug 2 and 3 respectively. The lowermost lug 2 fits in a corresponding groove in the back of said brake-block to form a tongue-joint, and the 55 lower end of said hanger has a bolt-hole 5 through which a screw 14 is passed to secure

it to said block. The lug 3 on the upper end of said hanger is fitted into a corresponding groove in a casting 7 to form another tongue-joint, and an orifice 4 permits entrance of a bolt 30, which, with the nut 6, serves to secure said hanger to said casting. A clamping plate 8 on the rear face of said hanger 1 is also secured by said last-mentioned bolt to hold the upper part of the 60 hanger tightly in place. The downwardly-projecting part 9 of said casting is somewhat diminished in thickness adjacent to said hanger, and has an interiorly-threaded orifice which receives an adjusting-screw 10 having a lock-nut 11 thereon, the end of the 65 screw bearing against the said hanger-plate and adapted to be turned to bring the plate 1 under tension to a desired degree. Referring to Fig. 2, it will be seen that the part 70 9 of said casting has a projection to the left provided with a channeled part 25 which is adapted to fit removably over the channeled support 12, and be secured thereto by means of bolts 23 and the nuts 24.

The hanger-plate 1 is held above to the casting 7 and below to the brake-block 15 rigidly by reason of its lugs 3 and 2 being seated in the corresponding grooves in said parts. This prevents slackness in the connections and consequent rattling, and preserves the screw 14 and bolt 30 from working loose, or working about in such a manner as to widen their seats in the connected bodies. The hanger-plate 1 may be put under a tension by means of the adjusting-screw 10 to keep the block 15 and shoe 21 at the right distance from the wheel-tread. The hanger-plate 1 then resiliently bears with said shoe in use against the tread with 95 good contact at all times.

Having described our invention, what we claim as new, and desire to secure by Letters Patent, is:

1. In combination, a supporting-body, a 100 spring-hanger, and a brake-head, said hanger being secured to said supporting-body and to said brake-head and means for placing said hanger under tension.

2. In combination, a supporting-body, a 105 spring-hanger, a brake-head, said hanger being secured to said supporting-body and to said brake-head by independent tongue-joints, and means for placing said spring-hanger under tension.

3. In combination, a supporting-body, a 110 spring-hanger, a brake-head, said hanger be-

- ing secured to said supporting-body and brake-head by independent tongue-joints, and adjustable means for placing said spring-hanger under tension, variably.
5. 4. In combination, a brake-block, a brake-shoe removably attached thereto, a flat spring-hanger, means for detachably securing said brake-block to one end of said hanger, means for placing said spring-hanger under tension, and means for securing the other end of said hanger detachably to a supporting-body.
- 10 5. In combination, a brake-block, a brake-shoe removably attached thereto, a flat spring-hanger, means for detachably securing said brake-block to one end of said hanger, adjustable means for placing said spring-hanger under a desired amount of tension, and means for securing the other 15 end of said hanger detachably to a supporting-body.
- 20 6. In combination, a brake-block, a brake-shoe removably attached thereon, a flat spring-hanger having a transverse lug on each end of one face thereof, said brake-block having a transverse groove on its rear face adapted to seat one of said lugs, a bracket adapted to be mounted on a supporting-body, said bracket having on its 25 rear face a transverse groove adapted to seat the other one of said lugs, means for
- attaching said spring-hanger detachably to the rear faces of said bracket and of said brake-block with its lugs secured in said grooves, and means adapted to place said 30 spring-hanger under tension.
7. In combination, a brake-block, a brake-shoe removably attached thereto, a flat spring-hanger having a transverse lug on each end of one face thereof, said brake-block having a transverse groove in its rear 35 face adapted to seat one of said lugs, a bracket adapted to be detachably mounted on a supporting body, said bracket having on its rear face a transverse groove adapted 40 to seat the other one of said lugs, means for detachably attaching said spring-hanger to the rear faces of said bracket and of said brake-block with its said lugs engaged in said transverse grooves, the lower part of 45 said bracket being spaced from said spring-hanger and an adjusting-screw seated movably in the spaced part of said hanger with its end bearing adjustably against the hanger to exercise a desired tension thereupon. 50
- 55 Signed at Waterloo, Iowa, this 29th day of Oct. 1912.
